Primary Examiner — Rosemary K Tarca*(74) Attorney, Agent, or Firm* — Sughrue Mion, PLLC(57) **CLAIM**

The ornamental design for a battery case, as shown and described.

DESCRIPTION

FIG. 1 is a front perspective view of a battery case showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in use; and,

FIG. 10 is a perspective view thereof in use.

The broken lines shown are included for the purpose of illustrating the unclaimed portions of the battery case and form no part of the claimed design.
